CHAIR

Walter C. Uline, Nappanee, Ind.

Application January 27, 1941, Serial No. 376,131

6 Claims. (Cl. 155—171)

This invention relates to improvements in chairs, and more particularly to high chairs for use by infants.

The primary object of the invention is to provide a chair of this character with a novel foot rest readily and easily adjustable for use by children of various sizes and ages.

A further object is to provide a chair of this character having a foot rest which is adjustable both vertically and horizontally to compensate for the growth of the femur and tibia of the legs of a child.

A further object is to provide a chair of this character having a foot rest which is supported in selected position relative to the seat by two members connected thereto at spaced points, and held in desired position with respect to the body of the chair by a single securing means.

A further object is to provide a foot rest pivoted on arms pivoted to a chair below the chair seat, and also having pivoted thereto swinging links in bodily shiftable relation to fixed points of a chair, and means for fixedly securing said arms and links relative to the chair.

Other objects will be apparent from the description and appended claims.

In the drawing:

Fig. 1 is a view of a chair in front elevation showing the front legs broken away to clearly illustrate my improved foot rest.

Fig. 2 is an enlarged fragmentary front detail view of the foot rest and its supporting means.

Fig. 3 is a fragmentary detail vertical cross-sectional view taken on line 3—3 of Fig. 2 and illustrating the foot rest in a raised position.

Fig. 4 is a view similar to Fig. 3 illustrating the foot rest in a lower horizontal position.

Referring to the drawing which illustrates the preferred embodiment of the invention, the numeral 10 designates the legs of a chair which are suitably interconnected by rungs 11 which extend horizontally between adjacent legs 10. A seat 12 is supported upon the legs 10 and in turn supports a back rest 13. A table 14 of suitable construction is mounted upon the chair by supporting members 15 and the like.

Two rungs 11 extend from the front to the rear legs of the chair at each side thereof, and an upright metal bracket 16 extends between the forward ends of said rungs 11 and is secured thereto in any suitable manner. The bracket 16 is preferably transversely configured for reinforcing purposes, and extends inwardly of said rungs to provide a vertical center portion 17 inset relative to vertical planes of the inner edges of the

5 rungs 11. The portion 17 is provided with a central opening (not shown), and a plurality of complementary ribs or off-sets 18 are impressed therein to extend in equi-spaced circular relation around said central opening. A bolt 19 extends through the opening in portion 17.

10 Each of the brackets 16 supports an arm 20. Each arm has an enlarged circular head portion 21 which is provided with a plurality of equi-spaced circularly arranged ribs or off-sets 22 15 therein and adapted to interfit with and complementary to the ribs 18 in bracket part 17. The opposite end of each arm 20 is pivoted at 23 to the front portion of one of a pair of brackets 24 which are secured to the lower face of a foot rest 25 adjacent opposite ends thereof.

20 It will be observed from the above that the foot rest 25 will swing bodily about the bolt 19 as a center, and that the spacing of the foot rest from the seat, as determined by the angular position of the arm 20, may be fixed by tightening the thumb nut 26 on screw 19 to press the faces of parts 17 and 21 in tight frictional contact with their complementary ribs or off-sets 18 and 22 25 in interfitting relation.

25 Each of a pair of links 27 is pivoted at 28 at one of its ends to the rear of each foot rest bracket 24, and is provided with an elongated longitudinal slot 29 at its opposite end. The slot 29 is normally slidable on screw or bolt 19 and may be secured in frictional face engagement with arm 20 upon tightening of the thumb nut 26.

30 This construction has the advantage of simplicity as to both its construction and its operation. Thus, for example, when it is desired to adjust the position of the foot rest 25 for the requirements of any particular child, it is necessary only to release the thumb nuts 26, swing arms 20 and slide the links 27 to position the foot rest at the desired height relative to the seat 12 and at desired inclination relative to the horizontal, and then to retighten the thumb nuts 26 to clamp the parts together.

35 This multiple adjustability permits the individual requirements of any child to be accommodated comfortably, and permits meeting and accommodating of changes in such requirements 40 as the child grows. The use of a single securing member for locking each pair of cooperating arms 20 and links 27 in proper adjustment makes for convenience of operation, simplicity, and reduced cost. Also, it will be observed that the 45 foot rest unit may be preassembled upon the

brackets 16, to be secured to the chair as a unit by simply securing the brackets to the chair.

I claim:

1. In a chair, the combination of a seat, a seat support including legs and interconnecting rungs therebetween, a pair of brackets fixedly carried by said seat support at opposite sides thereof, a pair of arms each pivoted at one end to one of said brackets, a foot rest having its ends pivotally mounted on the other ends of said arms, a pair of links each having one end thereof pivoted to said foot rest spaced from said arms, and means for locking the pivot connection between each arm and bracket in fixed angular position, said locking means also locking said links in desired relation to said brackets.

2. The construction defined in claim 1, wherein in said links have a combined pivotal and sliding connection with the bracket when said locking means are released.

3. The construction defined in claim 1, wherein in said last named means comprises complementary interfitting equi-spaced offsets and projections in said brackets and arms around said pivot, and means for clamping said brackets, arms, and links in frictional face engagement at the pivot center.

4. In a chair, a seat, means for supporting said seat, a foot rest, a pair of arms pivoted to

opposite ends of said foot rest, brackets carried by said seat supporting means, said arms being pivoted to said brackets, links pivoted to said foot rest spaced from said arms and having a normally slidable connection with said brackets, and means for locking said arms and links in fixed relation to said bracket.

5. In a chair, a seat, means for supporting said seat, a foot rest, a pair of arms pivoted to opposite ends of said foot rest, a pair of links pivoted to opposite ends of said foot rest in spaced relation to said arm pivots, and releasable means carried by said seat support for holding adjacent pairs of arms and links in desired relation to said seat support, said arms having a pivotal connection with said holding means and said links having a combined pivotal and slidable connection with said holding means when released.

20 6. In a chair, a seat, means for supporting said seat, a foot rest, a pair of arms, a pair of links, said arms and links being pivoted at opposite ends of said foot rest in spaced relation, said links being slotted, and means carried by said seat support and mounting said arms and links, said means including a securing member pivoting said arms and passing through the slots of said links.
